UNITED STATES PATENT OFFICE

2,447,617

ROTARY CUTTER

Seddon C. Nelson, Front Royal, Va., assignor to
 American Viscose Corporation, Wilmington,
 Del., a corporation of Delaware

Application June 9, 1945, Serial No. 598,545

3 Claims. (Cl. 164—39)

1

This invention concerns improvements in a cutter for filamentary material of the type shown in Beria Patent 1,723,998.

It is the chief object of the present invention to provide a rotary cutter of the type mentioned above with a rotary knife which is arranged to effect cutting by engagement with the disc periphery whereby such periphery serves as a co-operating shear member with the knife.

It is another object of the present invention to provide for reconditioning the knife during operation thereof. This reconditioning may involve the sharpening thereof, or it may involve the dulling of the knife to produce fibers of improved carding qualities as disclosed in the co-pending application of Welton, Serial No. 454,963, filed August 15, 1942, now Patent 2,411,644, November 26, 1946. A further object is to provide for the removal of any particles formed by the abrasive action of the reconditioning device. Further objects and advantages of the invention will be apparent from the drawing and the description thereof hereinafter.

In the drawing—

Figure 1 is a plan view of one embodiment of the invention;

Figure 2 is an elevation of the embodiment of Figure 1;

Figure 3 illustrates the operation of the embodiment of Figures 1 and 2 for dulling the knife;

Figure 4 is a side elevation showing a modification;

Figure 5 is an end elevation showing the relation of the conditioning device of Figure 4 to the knife;

Figure 6 is a plan view of a modification;

Figure 7 is an elevation of the embodiment of Figure 6, and

Figure 8 is a section of the vanned rotary cutter of Figures 6 and 7.

As shown generally in Figures 1 to 3, a cutter disc 2 is mounted for rotation within suitable bearings in a standard 3 and a platform 4, a pulley 5 being provided for receiving the driving motion through a belt. The disc is provided with an axial opening 6 into which the filamentary material in the form of a continuous yarn or tow may enter. The axial passage 6 is connected with the radial passage 7, which is adapted to discharge the filamentary material through the opening 8 in the periphery of the disc. A rotary cutter knife 9 is carried on a suitable standard or equivalent support 10, the knife being rotatably mounted upon the shaft 11 carried in the

2

supporting structure comprising the bracket 12 and an arm 13 of cylindrical construction arranged to extend into a bore within the bracket in which it may be adjustably set by means of set screw 14. In general, the axis of rotation of the knife 9 is so disposed as to extend transversely with respect to the axis of rotation of the disc, and so that the knife is in contact therewith throughout its rotation. The standard 10 likewise fits into a cylindrical bore within the bracket 12, so that it may be adjustably set by means of the screw 15 at any height and at any angular relationship with respect to the disc 2. The two set screws 14 and 15 thus provide for a universal adjustment. The rotary knife 9 preferably has a sloped or beveled back-facing 9a which may bear against the periphery of the disc 2 and assures rigidity of the knife during its cutting action which is effected by the leading edge 9b. The bracket 12 carries projections 16 in which an arm or lever 17 is pivotally mounted. The arm 17 carries a hone 18 or equivalent conditioning device such as an abrasive stone, and carries also a wiper such as a felt pad 19 positioned in advance of the hone and adapted to wipe off any abrasive particles loosened by means of the conditioning device 18 before the knife again comes into contact with the disc 2. A downwardly projecting member 20 is arranged to press the wiper against the backing face 9a, whereas the direct pressure of the extension 17a of the arm 17 serves to press the wiper into contact with the cutting edge. A counterweight 21 is adjustably secured upon a threaded end of the arm 17 so that the pressure of the conditioning device 18 against the knife 9 may be varied.

The axis of rotation of the knife 9 is offset laterally in a vertical direction from the area of contact of the periphery of disc 2 with the knife 9, so that the rotation of the disc 2 causes a simultaneous rotation of the knife 9. The amount of such lateral displacement may be varied at will merely by adjusting set screw 15. If desired, the axis of shaft 11 may be displaced 45 below instead of above the periphery 2, as shown in Figure 2.

Figures 4 and 5 illustrate a modification in which two conditioning devices are arranged so that the first one 18a is arranged to sharpen the cutting edge 9b (see Figure 5) whereas the second conditioning device 18b is arranged to dress the back face 9a of the knife. This arrangement may be used to effect sharpening of the knife, whereas the arrangement of Figures 1 to 3 is better adapted to the dulling of the blade.

Figures 6 to 8 show a modification in which the face of the blade 9 remote from the disk 2 is provided with a plurality of vanes 25. These vanes are inclined outwardly in the direction of rotation as shown in Figure 7 so that as the staple fibers are cut, the clumps thereof strike the vanes and are deflected downwardly, the impact serving to rotate the cutter blade. In this modification, the cutter mounting is changed in the following respects: The bracket 12 is freely rotatable on the standard 10 above a collar 26 fixed thereon. A weighted lever 27 having a cam surface 28 is mounted pivotally at 29 on a bracket 30 so that the cam surface bears against the bracket 12, thereby pressing the blade against the disk 2. In this embodiment, the axis of rotation of the cutter blade 9 may be substantially coincident with the plane of rotation of the axis of the radial bore 7, thereby causing the blade 9 to derive its entire component of rotary motion from the impacts of the fiber clumps. Alternatively, the axis of rotation of the blade may be offset from the plane of rotation of the axis of the radial bore of the disk to combine the impact with the offset relationship to impart rotation to the blade.

The cutter of the present invention requires less frequent dismantling for reconditioning of the knife. As compared to the type of Beria cutter heretofore used in which a stationary knife is employed, the rotating blade of the present invention has a greater surface over which wear is uniformly distributed during operation. In addition, the conditioning means further increases the life of the blade.

The cutting device of the present invention may be operated in such a manner that centrifugal force itself serves to draw the filaments through the passages 6 and 8. Alternatively, a lower speed may be used and a fluid jet, such as of air, or water, or other liquid, may be introduced into the axial passage 6 in order to forward the filamentary material. Whether or not reliance is placed solely upon centrifugal force, a liquid may be introduced with the filamentary material or upon the wiping pad to provide a lubricating effect. If desired, centrifugal force may be supplemented by a fluid jet and if desired, the fluid may be a liquid to provide a lubricating function in addition.

It is to be understood that the description is illustrative only, and that changes and variations may be made without departing from the spirit and scope of the invention as defined in the appended claims.

I claim:

1. Apparatus for cutting continuous filamentary material into discontinuous lengths comprising a rotatable disc having a radial passage for receiving the material and for discharging it radially outwardly from the disc, a rotatable cutting blade arranged to engage the disc periphery to co-operate therewith in effecting cutting of the material, the axis of rotation of the blade being disposed generally transversely with respect to the axis of rotation of the disc, and means interconnecting the blade with the disc for rotating the blade during rotation of the disc, said means being the sole means for rotating the blade.
2. Apparatus for cutting continuous filamentary material into discontinuous lengths comprising a rotatable disc having a radial passage for receiving the material and for discharging it radially outwardly from the disc, a rotatable cutting blade arranged to engage the disc periphery to co-operate therewith in effecting cutting of the material, the axis of rotation of the blade being disposed generally transversely with respect to the axis of rotation of the disc, and means comprising vanes on the blade for rotating the blade during rotation of the disc.
3. Apparatus for cutting continuous filamentary material into discontinuous lengths comprising a rotatable disc having a radial passage for receiving the material and for discharging it radially outwardly from the disc, a rotatable cutting blade to engage the disc periphery to co-operate therewith in effecting cutting of the material, the axis of rotation of the blade being disposed generally transversely with respect to the axis of rotation of the disc, the axis of rotation of the blade being offset laterally from a central radial plane of the rotatable disc, the rotation of the blade being the result solely of the offset relationship between the interengaging blade and disc.
